UNITED STATES PATENT OFFICE.

JOSEPH H. WITTMANN, OF KANSAS CITY, MISSOURI.

CAMP-TOILET.

1,306,041.

Specification of Letters Patent.

Patented June 10, 1919.

Application filed October 22, 1917. Serial No. 197,825.

To all whom it may concern:

Be it known that I, JOSEPH H. WITTMANN, a citizen of the United States, residing at Kansas City, in the county of Jackson and State of Missouri, have invented certain new and useful Improvements in Camp-Toilets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to camp toilets and has for its principal object to provide a sanitary, portable toilet stool which may be conveniently carried by automobile tourists, or others, and may be easily and quickly set up and knocked down upon making or breaking camp.

In accomplishing this object, I have provided improved details of structure, the preferred forms of which are illustrated in the accompanying drawings, wherein:

Figure I is a perspective view of a camp toilet embodying my invention, illustrating its connection with a supporting standard and its inclosure in a portable tent.

Fig. II is an inverted perspective view of a stool, particularly illustrating its sanitary lining.

Fig. III is a top perspective view of the same.

Fig. IV is an enlarged elevational section of part of the stool, particularly illustrating the anchor bar.

Fig. V is a detail perspective view of the anchor bar.

Referring more in detail to the drawings:

1 designates a front support and 2 a seat member forming the body of a toilet stool, the said members being connected by hinges 3 at their upper and forward edges in order that they may fold against each other to form a compact body that may be arranged compactly for convenient transport and storage, each member being preferably formed from a single board or sheet of material and the seat member 2 provided with any suitable number of openings 4.

The top board 2 is, in the preferred form, provided with two openings 4, as this arrangement allows the placement of the openings at opposite sides of a central support and avoids any interference by said support

with the clearance that is desirable beneath the seat.

The front board 1 is provided along its upper edge and at the center of the board, 60 with a downset slot 5 for receiving an anchor and seat supporting bar 6, having a notch 7 at its rear upper corner for receiving a batten 8 that is suspended from the rear edge of the seat board 2, and provided at its forward end with a loop strap 9 through which a suitable tie member 10 may be projected to attach the anchor bar to any suitable standard when the stool is set up; the anchor bar being rigidly connected with the front 70 board 1, when the parts are assembled, by a pin 11 that is projected through the eyes 12 of the hinge members 13—13' on the front and under edge of the front board 1 and anchor bar 6 respectively. The stool comprises merely the front and top board, as 75 ends and a back are undesirable for either sanitation or support in a temporary toilet. To further render the stool sanitary, I preferably provide the front board 1 with a removable sheet 14 of paper or other suitable material, which may be temporarily attached to the stool by locating the upper edge of the sheet between the upper edge of the front board 1 and the bottom of the seat member 2 80 when the parts are being set up, to clamp the upper edge of the sheet therebetween; the lower edge of the sheet being turned under the bottom of the front board and attached 85 thereto by tacks or the like 15.

It is apparent that with this arrangement the sheet 14 may be attached to the front part of the stool before it is erected and that when the stool is taken down for transportation the sheet may be removed, to be replaced 95 by a fresh one when the toilet is again put to use.

While the complete stool comprises the hingedly connected front board and seat, the anchor bar 6 and tie member 10, these parts 100 may be supplemented by a tent 15' of any suitable construction and which may be erected on a tree or other standard 16, to which the front end of the anchor bar is attached, and pinned securely at its corners. 105

The complete toilet, including the seat, may be carried in a compact bundle in an automobile or wagon and when intended for use may be assembled by arranging the front support and seat at a right angle to each 110 other and projecting the anchor bar through the slot 5 in the upper edge of the front

board until the notch 7 seats against the bat-
ten 8 on the seat member. The hinge pin 11
is then projected through the eyes 12 of the
hinge member 13—13' on the front member
5 1 and anchor bar respectively, and the front
end of the anchor bar attached to a tree or
other standard by means of a rope or the
like.

Before the anchor bar is attached to its
10 standard, the sanitary lining 14, which may
comprise several thicknesses of paper or
other material, is placed on the front board
by projecting the upper edge of the sheet be-
tween the meeting surfaces of the front 1
15 and seat 2 and the lower edge of the sheet
turned under the bottom of the supporting
front board and tacked to the front face
thereof. With the stool anchored to the tree,
it is supported from the front board 1 and
20 the latter is held from tipping by its anchor-
age to the tree or other standard, the anchor
bar extending beneath the seat to form a
support therefor, although the principal
weight would naturally be located on the
25 front of the seat over the edge of the front
board.

The toilet, when so constructed, may be
used during the camping period and when
the camp is broken may be easily and quickly
30 taken down by disconnecting the anchor
bar from tree or standard and the stool re-
moved in a body from its point of use. The
anchor bar may then be disconnected from
the stool body and before the seat is folded
35 onto the front board, the upper edge of the
sanitary sheet 14 removed from between the
stool members and detached from the front
board by removing the tacks or tearing the
sheet therefrom.

40 With the sanitary sheet removed, the seat
may be folded onto the front board and the
parts assembled in portable relation and
stored conveniently within the vehicle or
elsewhere.

45 It is apparent, therefore, that the struc-
ture not only affords a compact, convenient
device for the use intended, but, by the ad-
dition of the sanitary sheet, provides a clean
and sanitary stool which may be carried
50 conveniently and comfortably with other
camp equipment.

Having thus described my invention, what

I claim as new therein, and desire to secure
by Letters-Patent is:

1. A portable toilet comprising a seat 55
member, a support anchored perpendicu-
larly to the seat member, and an anchor bar
underlying the seat member and projecting
through the support.

2. A portable toilet comprising a seat 60
member, a front board supporting the seat
member from the forward edge thereof and
an anchor bar underlying the seat member
and extended through the front board.

3. A portable toilet comprising a seat 65
member, a front board supporting the seat
member from the forward edge thereof, an
anchor bar underlying the seat member and
extended through the front board, and
means temporarily connecting the front 70
board and anchor bar.

4. A portable toilet comprising a seat
member, a front board supporting the seat
member from the forward edge thereof, an
anchor bar underlying the seat member and
extended through the front board, eye mem-
bers on the front board and anchor bar, and
a pin removably located in said eye members.

5. A portable toilet comprising a seat
member, a front board supporting the seat 80
member from the forward edge thereof, an
anchor bar underlying the seat member and
extended through the front board, and
means at the front end of the anchor bar
for connecting the bar with an independent 85
body.

6. In a portable toilet, collapsible seat
and front members, and a lining having its
upper edge clamped between said members
and its lower edge turned beneath and at-
tached to said front member, to protect the
inner surface of said member.

7. In a device of the class described, a top
member, a front supporting member hinged
thereto, and an anchor bar carried by the
top member having means for attachment
to a support.

8. In a device of the class described, a top
member, a front supporting member hinged
thereto, and a transversely projecting an-
chor bar carried by the top member having
means for attachment to a support.

In testimony whereof I affix my signature.

JOSEPH H. WITTMANN.
